FRANK J. MAYNARD, OF ST. LOUIS, MISSOURI

STORAGE BATTERY TOOL

Application filed July 18, 1929. Serial No. 379,081.

My invention relates to improvements in storage battery tools, and has for its primary object a storage battery tool for loosening up the cable terminals on storage batteries when they have become corroded on the binding posts.

A further object is to construct a tool for removing cable terminals, which is so arranged that a gradual steady pressure can be applied to the cable terminal for spreading it thereby loosening the same from the binding post. Heretofore it has been frequently necessary to use a cold chisel or similar device to loosen up corroded terminals with the result that quite frequently the binding post was broken off in which event the battery had to be taken apart and a new post placed in position. This caused considerable loss to the owners of charging stations because they had to make the damage good at their own expense. With my device, however, no pounding or hammering is necessary and it is not necessary to twist the terminal in order to loosen it. This twisting was the most frequent cause of the breaking off of binding posts.

In the drawings:

Fig. 1 is a fragmental view of a battery showing a binding post with a cable terminal thereon and showing my tool in operative position; and

Fig. 2 is an edge view of the battery tool.

In the construction of my device I employ a pair of members 3 and 4. These members are pivotally united by means of a bolt 5. The members are provided with an opening 6 through which the bolt passes, the bolt being so constructed that the tool will be adjustable as to the spread of the jaws. The member 3 is provided with a jaw 7, which is recessed as indicated by the numeral 8. The purpose of this recess will be explained in detail later.

The arm 4 is provided with a jaw 9. The jaw 9 is shorter than the jaw 8 and has its edge provided with serrations 10. The jaw 9 also is relatively thin so that its end adjacent the serrations is wedge-shaped. 11 represents a battery cable which has its end secured in the socket 12 carried by the battery terminal. Formed integral with the

socket 12 is a ring 13, which is adapted to fit around the terminal post 14. The ring is split and is provided with ears 15 and 16 through which a bolt 17 extends. The bolt 17 is provided with a nut 18 by means of which the ears 15 and 16 can be drawn together so as to cause the ring 13 to bind tightly around the terminal post 14. It is a well known fact that corrosion occurs at each terminal post, this corrosion extending even to the bolt 17 so that in time this bolt becomes corroded in the ears 15 and 16. The ears 15 and 16, however, do not quite touch when the terminal is secured to the post but leaves a relatively narrow opening sufficient so that the serrated end of the jaw 9 can be inserted therebetween.

The jaw 9 is also provided with a heel 19, which can be tapped with a hammer so that the serrations will be forced into the opening. As a usual rule, however, this tapping is not necessary.

The operation of the device is as follows: The first step is to loosen the nut 18 and back it some distance away from the ear 16. The jaw 9 is inserted in the space left between the ears 15 and 16, and the jaw 7 so placed that either the end of the bolt or the nut 18 will enter the recess. Then the handles of the members 3 and 4 are pressed together forcing the jaws 7 and 9 toward each other. This exerts a pull on the ear 16 causing it to slide along the bolt thereby spreading the ring 13 and permitting the ready removal of the cable clip. I have found that in most every instance the bolt 17 is so firmly corroded in the ear 15 that when the jaws of the tool are pressed together the ear 16 will move along the bolt thus permitting the ring 13 to spread.

The cable tool can be placed in position as either indicated in Fig. 2, this is laid in a horizontal position, or it may be placed vertically. In either event the operation is the same. The position in which it is placed being optional with the party using the tool. It will be seen from the foregoing that there is only a pressure exerted on one ear and this pressure being gradual and non-twisting on the battery terminal, there is no danger of

the same becoming broken or twisting off. Then, again, it is not necessary with my device that the jaws be inserted underneath the clip. Consequently there is no danger of mashing in a cover of the battery of the jar. In fact all pressures exerted by my device are only on the bolt and one ear of the clip, and this pressure is a gradually exerted pressure with no violent blows or twisting.

10 Having fully described my invention, what I claim is:—

A storage battery tool comprising a pair of members pivotally united intermediate their ends, a jaw having a sharp inturned edge formed on one of said members, said edge extending transversely of said member and being serrated, a flat recessed jaw formed on the remaining member and being longer than the first-mentioned jaw, and a heel 15 formed on the serrated jaw.

20 In testimony whereof I have affixed my signature.

FRANK J. MAYNARD.
